UNITED STATES PATENT OFFICE.

HACHIG A. AYVAD, OF HOBOKEN, NEW JERSEY.

DESIGN FOR A LIFE-PRESERVER BODY.

SPECIFICATION forming part of Design No. 35,550, dated January 7, 1902.

Application filed December 2, 1901. Serial No. 84,480. Term of patent 14 years.

To all whom it may concern:

Be it known that I, HACHIG A. AYVAD, a citizen of the United States, and a resident of Hoboken, in the county of Hudson and State of New Jersey, have invented and produced a new and original Design for Life-Preserver Bodies, of which the following is a specification, reference being had to the accompanying drawings, forming a part thereof, and in

to which—

Figure 1 is a plan view of a bag or body of a life-preserver, showing my new design; and Fig. 2 is an edge view.

As shown in the drawings, the leading or material features of my design are an oblong body formed with convexly-curved corners lying within the angles formed by the four sides, one side of the body having a deep intermediate recess. Said oblong body is com-

posed of two lobe-shaped portions A A' and 20 an intermediate neck B at one side, thus forming at the opposite side of the body a deep recess C. The side edges D of the body are straight, while the corners D', lying within the angles formed by the edges D, are convexly curved. A marginal ornamentation E is also provided.

What I claim as new and of my invention is—

The design for a life-preserver body, substantially as shown and described.

Signed at New York this 27th day of November, 1901.

HACHIG A. AYVAD.
